GLUING AND SHEETING MACHINE

John A. Heckman, Chicago, Ill., assignor to Miller
Wrapping and Sealing Machine Company, Chi-
cago, Ill., a corporation of Illinois

Application February 24, 1938, Serial No. 182,832

13 Claims. (Cl. 91—49)

An object of this invention is to provide a machine for automatically advancing a web from a roll of Cellophane or the like, applying a strip of glue or wax to one or both side edges, applying a line of glue or wax transversely of the web and severing the web to form a sheet.

Another object is the provision of apparatus for applying a strip of glue or a plurality of dots or a single dot of glue as desired to one or both side edges.

Another object is to provide means for applying a transverse line of glue to a web or sheet.

Still another object is to provide a means for floating the gluing mechanism on the roll on which the web passes so as to render uniform the application of glue to the web.

These and other objects, as will hereinafter appear, are accomplished by this invention which is fully described in the following specification and shown in the accompanying drawings in which

Figure 1 is a side elevation of a machine embodying the invention;

Fig. 2 is a partial enlarged vertical section on line 2—2 of Fig. 1;

Fig. 3 is a top plan view of Fig. 2;

Fig. 4 is a partial vertical section on line 4—4 of Fig. 3;

Fig. 5 is an enlarged front elevation of the transverse gluing mechanism of Figs. 2, 3 and 4 showing the glue pot partly in section, the gluing disk in an inoperative position wherein it seals the spout from the glue pot;

Fig. 6 is a similar view showing the gluing disk in operation wherein its periphery is receiving glue from the spout;

Fig. 7 is a partial enlarged view on line 7—7 of Fig. 2;

Fig. 8 is a partial enlarged vertical section on line 8—8 of Fig. 2 showing the cutting and longitudinal gluing mechanism;

Fig. 9 is a partial view on the broken line 9—9 of Fig. 2; and

Figs. 10, 11 and 12 are plan views of the sheet during the process of being glued and cut.

The embodiment illustrated comprises a gluing and sheeting machine having a main frame 13 having side frame members 14, 15.

A roll A of Cellophane or the like is mounted to turn in the frame and a web A¹ passes up over an idler roller 16 and over an operating roller 17 thence under a transverse gluing mechanism B and beneath a knife C where the sheet is severed. After this, the detached sheet A² (Fig. 12) passes on to the continuously operating belt con-

veyor 18 (Fig. 8) which is driven in any suitable fashion and which is not shown in detail as it forms no part of the present invention. As the web passes under the roll 17 it is glued along the lines D¹ and D² (Fig. 10) by the mechanism represented generally as D in Figs. 2 and 8. Then, after the sheet has passed around the roll 17 and has been brought to rest, as will later be described, the transverse gluing mechanism 10 B applies glue to the sheet beginning at the point B¹ (Fig. 10) and traveling downward across the sheet so as to make a complete glue strip B² (Fig. 11). At the same time, the shearing mechanism C starts a cut which likewise travels 15 across the sheet completely severing the sheet A² which then in Fig. 12 is propelled by means of a conveyor 18 to a table 19 (Fig. 1) where it may be picked up by an operator or by one of several operators and wrapped and folded about a package to be wrapped in a manner well known in this art.

The mechanism for effecting these automatic operations consists of an oscillating lever 20 which is connected to a shaft 21 which is mounted in suitable bracings on the frame of the machine. This shaft carries an operating lever 22 which is connected by means of a connecting rod 23 to a pin 24 on a gear 25 which is mounted on a shaft, not shown, and geared to a pinion 26 which is mounted on a shaft which also carries a sheave or pulley 27 which is driven by a motor 28 by means of a suitable belt 29.

The lever 20 has an extension 30 which carries a cam follower roller 30^b which acts upon a cam 31 which is mounted on an oscillating lever 32 which is pivotally mounted at 33 on the side of the frame. The lever 32 is connected to a vertical link 34 which connects at its upper end with the outer end of a knife 35 (Fig. 2) which is connected at the opposite end on a pivot 36 and which is moved up and down about the pivot 36 as shown in full and dotted lines in Fig. 8. As it descends, the movable knife 35 passes the stationary knife 37 over which passes the sheet A¹ thereby severing the same to produce the sheet A².

Upon the lever 20 is mounted a member 38 which is adjustable up and down by means of a screw 39 so as to vary the length of web fed at 50 each actuation of the lever 20, the throw of the lever remaining constant. A bar 40 having a rack formed on its upper surface is connected at this lower end to the member 38 while the rack meshes with a pinion 40'. The pinion is connected to the roll 17 by means of a suitable ratchet ar-

angement so that as the bar 40 moves to the right, the roll 17 will be normally driven to feed forward the web A¹, but upon reversal of movement of the bar 40, the roll 17 remains stationary.

The mechanism B for producing the glue line B² will now be described. This comprises a carriage 41 (Fig. 7) which is slidably mounted upon guide rods 42, 43, which are suitably carried by the main frame. To the carriage 41 is pivotally mounted a member 44 means of a pin 45, the same being normally drawn down by gravity assisted by a spring 46 (Fig. 3). The member 44 carries a glue pot 47 which is secured thereto by means of a screw 48 (Fig. 5). The level of the glue or wax is shown by the numeral 49.

A gluing disk 50 is pivotally mounted at 51 on a lever 52 which in turn is pivotally mounted at 53 on the glue pot 47 in the normal inoperative position shown in Fig. 5. The disk 50 has a flat periphery which rests against a spout 54 which connects with the bottom of the glue pot 47. In this position, the disk 50 which is wide enough to cover the spout 54 serves to close the same so that glue or the like in the glue pot will not flow out. The weight of the disk 50 normally serves to close the opening in the spout and gravity is assisted by a spring 55 which is placed about a screw 56 passing through an arm 57 rigidly mounted to the glue pot, said screw serving to regulate the distance the disk 50 can leave the spout 54. This distance will thus fix the depth of the film of glue 58 of Fig. 6 which is shown being applied to the web A¹ to form the strip of glue B² of Fig. 11.

Thus it will be seen that glue will only be fed to the disk while it is in contact with the web.

The mechanism for bringing this disk into contact with the web will now be described. A cam follower block 59 is pivotally mounted on a pin 60 in the member 44 and is normally pressed upwardly as viewed in Fig. 5 and in a clockwise direction as viewed in Fig. 3 by means of a spring 61. The block 59 has a pin 62 on which is rotatably mounted a cam follower roller 63.

The carriage 41 is moved back and forth on the guides 42, 43 by means of a steel rope 64 which is secured thereto by means of a screw 65 as shown in Fig. 7. Referring to Fig. 2, the rope 64 passes around sheaves 66, 67 and 68 which are suitably mounted on the main frame. The two vertical sections of the rope 64 at the left of Fig. 2 are shown in Fig. 1 where they pass around sheaves 69, 70 which are also carried on the main frame. One end of the rope 64^a passes around the sheave 69, then passes around a sheave 71 on a lever 30^a connected to the lever 30, and is fastened to a stationary pin 72 on the main frame.

The opposite end of the rope 64^b, after leaving the sheave 70, passes around a sheave 73, thence around a sheave 74, also on the lever 30^a and has its end secured to the main frame at 75.

Thus, it will be seen that as the lever 20 is rocked back and forth, the rope 64 will be fed back and forth thereby drawing with it the carriage 41 of Fig. 7 and the gluing disk 50. This disk is raised and lowered by means of longitudinal cams over which the cam follower roller 63 passes. These cams are shown in Figs. 3 and 4. This transverse gluing mechanism is normally in the position shown at the left hand side of Fig. 3 and the right hand side of Fig. 4.

With the parts in this position, as the carriage moves to the right in Fig. 3 and to the left in Fig. 4, the roller 63 rides up on a longitudinal cam or runway 76 and is held there by the spring 61 and

5 by means of a stop 59^a on the block 59. As the roller moves forward, it follows the cam 76 as shown in the position 63^a (Fig. 4) until it reaches a point near the opposite end of its travel 63^b at which point it engages a deflector 77 which forces it back against the action of the spring 61 and it follows to the position 63^b where it rests on the top of a cam 78. The vertical edge of the cam 78 prevents the roller from again climbing back on the latter cam and causes it to follow the top surface of the cam 78.

15 As the carriage 41 is now returned toward the right in Fig. 4, the roller 63 drops off the end of the cam 78 as shown at 63^c. Up to this time, the gluing mechanism of Fig. 5 has been raised so that the disk 50 is out of contact with the web A¹, but as the roller 63^c runs off the cam 78 the disk 50 is dropped into contact with the web A¹ as shown in Fig. 4 and as the gluing mechanism is propelled to the right, the disk 50 will remain in contact with the web until the roller reaches a position 63^d in which it runs up the face of an inclined cam 79. Between the positions of rollers 63^c and 63^d, the disk 50 has been in contact with the web A¹ and has rolled thereon thereby depositing a strip of glue B² as shown in Figs. 4 and 6. The roller then continues to move to the right in Fig. 4 from the position 63^d to the position 63 at which point it has passed the end of the cam 76 and the spring 61 again forces the roller over to a position where it will again ride up on top of the cam 78 when the follower is again moved to the left.

35 The cams 78 and 79 are mounted on a screw 80 which has right hand threads on one end and left hand threads on the other, the screw being suitably journaled in the frame that supports the guides 42 and 43 and having an adjusting handle 81 for rotating it so as to adjust the distance between the cams 78 and 79, thereby adjusting the length of the glued strip B².

40 The mechanism for applying the longitudinal strips of glue D¹ and D² will now be described. The parallel gluing mechanisms D of Fig. 2 and 8 are mounted on arms 82 which are slidably and adjustably mounted upon a hollow shaft 83 which carries a spline or key 84, these arms being adjustable longitudinally of the shaft 83 by means of the screws 85 and key 84. This shaft is rotatable in suitable bearings 86, 87 which are carried by the main frame.

45 The arm 82 (Fig. 8) carries a guide pin 88 on which is slidably mounted a member 89 which has an adjusting screw 90 at its lower end, the head of this screw normally being held up against the end of the pin 88 by means of a spring 91. The member 89 has secured thereto a glue pot 92 in which rotates a gluing disk 93 which dips in the glue, the level of the latter being shown by the number 94. The glue pot is covered by a suitable adjustable lid having a slot through which the glue disk 93 operates. A finger 95 at each side of this disk removes glue from the sides of the disk. A pressure roller 96 is mounted to roll on the pin 97 at the upper end of a pressure lever 98 which is pivotally connected to the upper end of the lever 82 by means of a pin 99. A spring 100 connects the levers 82 and 98 and its center lying inside the pin 99 constantly tending to keep the roller 96 in contact with the roll 17 so as to exert a slight pressure on the web A¹ passing around the roll 17 so as to hold the web in contact therewith.

50 With the gluing mechanism in the dotted line position of Fig. 8, the gluing disk 93 is out of

contact with the web and consequently no glue is applied. When, however, the gluing disk is moved back to the full line position of the gluing disk 93, the latter is in contact with the web and glue will be applied thereto to form the longitudinal glue lines D¹, D² of Fig. 10.

The method of moving the shaft 83 to accomplish this will now be described. Referring to Fig. 1, a cam follower 101 is mounted on the end of a lever 102 which is pivotally mounted at 103 on the side of the frame. Cams 104 and 105 are mounted on a carriage 106 which is slidably mounted on guides 107 which are carried by a bracket 108 secured to the main frame. The carriage is connected by means of a link 109 to the oscillating lever 20 so as to be moved back and forth as the lever is oscillated.

The cam 104 has a support 104a which is threaded to receive an adjusting screw 110 which has an adjusting lever 111. Similarly, the cam 105 has a support 105a which is threaded to receive a screw 112 which has an adjusting lever 113. Thus it will be seen that each of the cams 104 and 105 is individually adjustable back and forth with respect to the follower 101 with which they cooperate. As will later be seen, the gluing mechanism is held in the dotted line position of Fig. 8 in which it is inoperative so long as the follower 101 rides on top of either of the cams 104 or 105. By bringing these cams therefore together, neither of the longitudinal glue lines D¹ or D² would be formed on the web. By a reverse mechanism, however, which will later be described, this method of operation will just be reversed and gluing will take place only when the follower 101 rides on top of one or other of the cams 104 or 105. The cam follower lever 102 (Fig. 9) carries two projections 114 and 115. The shaft 83 is hollow and journaled therein for oscillation is a reversing shaft 116 having a reversing lever 117 which is normally urged toward the right by means of a spring 118. The opposite end of the shaft 116 carries a reversing lever 119 which has one or more teeth 120 adapted to engage in slots 121 in a clutch 122 secured to the end of the shaft 83. The outer end of the reversing lever 119 is provided with adjusting screws 123, 124. The screw 123 is adapted to engage the projection 114 while the screw 124 engages the projection 115.

Normally this reversing mechanism will be operated in the full line position in which the lever 119 is operated by the projection 114 on the cam follower lever. In this position, glue will be applied by the gluing disk 93 only so long as the follower 101 does not ride upon either of the cams 104 or 105. So long as it does ride upon one of these cams, the gluing mechanism D will be held in the dotted line position of Fig. 8 and is released to the full line position when the follower runs off these cams. It will be apparent, however, that by reversing the lever 119 to the dotted line position of Fig. 9, the action of the shaft 83 will be exactly reversed and the glue will be applied so long as the follower 101 is raised by either of the cams 104 or 105, and that no glue will be applied when the cam follower is off both of these cams.

Thus it will be seen that this latter arrangement in which the lever 119 is in the dotted line position of Fig. 9, two spots of glue may be applied instead of one, or a single spot of glue may be applied at one end only of the web. This is particularly useful where the sheet to be cut is quite small and it is necessary to apply a spot or

line of glue to the web considerably in advance of cutting the sheet, or in the case of a large sheet.

Thus it will be seen that a very flexible arrangement has been provided for applying glue to sheets covering a wide variety of shapes and sizes. If desired, the glue may be replaced by a wax. After the wax has been applied to the sheet and cooled, it may be heated to cause overlapping portions of the sheet when folded about a package to adhere.

I claim:

1. In mechanism of the class described, means for intermittently advancing a web, means for applying glue to a predetermined line along one edge of the web while it is advancing, and transversely movable means for applying a line of glue transversely of the web.

2. In mechanism of the class described, a roll over which passes a web, a glue pot having a gluing disk rotatable therein to pick up a film of glue on its periphery, a lever mounted to rotate about an axis, the glue pot being slidably and yieldably mounted on the lever, and means for moving the lever so that the disk will be moved into and out of engagement with the web as it passes around the roll as the lever is moved.

3. In mechanism of the class described, a roll over which passes a web, a glue pot having a gluing disk rotatable therein to pick up a film on its periphery, a lever mounted to rotate about an axis, the glue pot being slidably mounted on the lever, a stop for the glue pot, a spring for normally yieldably holding the glue pot against the stop, and means for moving the lever so that the disk will be moved into and out of engagement with the web on the roller as the lever is moved.

4. In mechanism of the class described, a roll over which passes a web, a glue pot having a gluing disk rotatable therein to pick up a film of glue on its periphery, a member on which the glue pot is slidably mounted, a stop for limiting the upper movement of the glue pot, a spring tending to hold the glue pot in engagement with the stop, and means for moving the member to cause the gluing disk to engage the web.

5. In mechanism of the class described, a roll over which passes a web, a glue pot having a gluing disk rotatable therein to pick up a film of glue on its periphery, a lever mounted on a shaft, the glue pot being operably mounted on the lever, and means for rocking the shaft to cause the disk to engage the web as it passes over the roller, said means including a cam, a cam follower, a cam follower lever, and a lever operably connecting the cam follower lever to the shaft, the last-mentioned lever being reversible so as to cause the action of the gluing disk to be reversed upon motion of the cam follower.

6. In mechanism of the class described, a roll over which passes a web, a glue pot having a gluing disk rotatable therein to pick up a film of glue on its periphery, a lever mounted to rotate about an axis, the glue pot being slidably and yieldably mounted on the lever, means for moving the lever so that the disk will be moved into and out of engagement with the web as it passes around the roll as the lever is moved, a second lever pivotally mounted on the end of the first-mentioned lever, a roller on the free end of the second lever, and spring means for urging the roller toward the roll to yieldably hold the web against the roll.

7. In a gluing and sheeting machine, means

for intermittently advancing a web to be glued and sheeted, means for applying a line of glue to one side of the web as it is advanced, means traveling transversely of the web and movable into and out of contact therewith for applying a transverse line of glue, means for adjusting the range of contact of the glue-applying means with the web to limit the lengths and positions of the lines of glue with respect to the web, and means for cutting a glued sheet from the web.

8. In a gluing and sheeting machine, means for intermittently advancing a web to be glued and sheeted, means for applying a line of glue to one side of the web as it is advanced, means traveling transversely of the web for applying a transverse line of glue, and mounted for movement into and out of contact with the web, means for actuating said glue-applying means including cams, and means for adjusting said cams to vary the lengths and positions of the lines of gluing contact with respect to the web.

9. In a gluing and sheeting machine, means for intermittently advancing a web to be glued and sheeted, means for applying a line of glue to one side of the web as it is advanced, means traveling transversely of the web for applying a transverse line of glue, and mounted for movement into and out of contact with the web, means for actuating said glue-applying means including cams, means for adjusting said cams to vary the lengths and positions of the lines of gluing contact with respect to the web, and means for reversing the action of the cams with respect to the glue-applying means.

10. In a gluing and sheeting machine, means for intermittently advancing a web to be glued and sheeted, means for applying a line of glue to one side of the web as it is advanced, means traveling transversely of the web and movable into and out of contact therewith for applying a transverse line of glue, and means for adjusting the range of contact of the glue-applying means with the web to limit the lengths and positions of the lines of glue with respect to the web.

11. In a gluing mechanism, means for advancing a web, a glue pot having a spout, a gluing

disk having its periphery in close proximity to the spout and rotatably mounted upon an arm which is pivotally mounted with respect to the spout, the glue pot being pivotally mounted at a point remote from the disk for normally holding the disk in closing contact with the spout, means for guiding the glue pot and disk in movements across the face of the web, a runway in contiguous relation to said guiding means, and 5 an element connected with the glue pot and adapted to travel upon said runway for tilting the glue pot toward and from the web to effect contact with the web and by relative movement of the glue pot and disk to open the spout for 10 the discharge of glue and by reverse movement 15 to close the spout.

12. In a gluing mechanism, a glue pot having a spout, means for imparting relative movements of the spout over the face of a web, a gluing device normally standing in yieldable contact with the spout to close the same against the discharge of glue, and automatic means for moving the spout and gluing device toward and from the face of the web at predetermined intervals and adapted when the gluing device contacts the web, by additional movement of the spout toward the web, to cause withdrawal of the gluing device from contact with the spout to permit the discharge of glue.

13. In a gluing mechanism, a glue pot having a spout, means for imparting relative movements of the spout over the face of a web, a gluing device normally standing in yieldable contact with the spout to close the same against the discharge of glue, automatic means for moving the spout and gluing device toward and from the face of the web at predetermined intervals and adapted when the gluing device contacts the web, by additional movement of the spout toward the web, to cause withdrawal of the gluing device from contact with the spout to permit the discharge of glue, said automatic means including a runway having thereon a cam, and an element connected with the spout and adapted to travel upon said runway and cam.

JOHN A. HECKMAN.
